UNITED STATES PATENT OFFICE.

ISAAC E. PALMER, OF MIDDLETOWN, CONNECTICUT.

DESIGN FOR A HAMMOCK.

SPECIFICATION forming part of Design No. 28,306, dated May 22, 1894.

Application filed April 13, 1894. Serial No. 507,485. Term of patent 14 years.

To all whom it may concern:

Be it known that I, ISAAC E. PALMER, of Middletown, in the county of Middlesex and State of Connecticut, have invented and produced a new and original Design for Hammocks, of which the following is a specification, reference being had to the accompanying drawings, forming a part thereof.

The leading feature of my design is the shape of the hammock provided with the outer shorter or shallower valance extending from the sides and ends of the body of the hammock and the longer or deeper inner valance, also extending from the sides and ends of the hammock, producing—when the hammock is strung for use—a flounced and box-like appearance, as shown.

Figure 1 represents the appearance which the parts present when they are laid out in a plane and Fig. 2 the appearance which they ²⁰ present when strung for use.

A represents the body of the hammock, *a* the outer shorter or shallower valance and B the inner longer or deeper valance.

What I claim is—

The design for a hammock, substantially as herein shown and described.

ISAAC E. PALMER.
